Primary Examiner — Calvin E Vansant*Assistant Examiner* — Mark T. Philippss(57) **CLAIM**

The ornamental design for a blowtorch as shown and described.

DESCRIPTION

1.1 is a rear view.

1.2 is a top plan view.

1.3 is a front view.

1.4 is a right, top, rear perspective view.

1.5 is a right-side view.

1.6 is a left-side view.

1.7 is a bottom plan view.

An atmospheric blowtorch for hand guided use in perspective view on handle from rear, two side views, front view, rear view, top view and bottom view; The blowtorch has a kinked shape with a lower handle portion and an upper nozzle portion; Miscellaneous control elements are located near to the kink.

The broken lines in the drawings depict portions of the blowtorch that form no part of the claimed design.

1 Claim, 7 Drawing Sheets(56)
